Patented Oct. 3, 1922.

2 SHEETS—SHEET 2.

UNITED STATES PATENT OFFICE.

CLARENCE H. BLACKALE, OF CAMBRIDGE, MASSACHUSETTS.

BUILDING CONSTRUCTION.

Application filed April 13, 1921. Serial No. 461,141.

To all whom it may concern:

Be it known that I, CLARENCE H. BLACKALE, a citizen of the United States of America, and resident of Cambridge, in the county of Middlesex and State of Massachusetts, have invented new and useful Improvements in Building Construction, of which the following is a specification.

This invention relates to building combinations and more particularly to constructions whereby chairs, tables or other isolated or grouped objects may be adjustably attached to floors, walls, ceilings or other portions of a building formed entirely or in part of concrete or other cast, moulded or troweled compositions.

In fastening theatre chairs to a concrete floor, for example, it is desirable to align the chairs either in straight lines or in curves and also to space them uniformly apart. In the case of sloping floors it is also necessary to fasten the chairs in an inclined position relative to the floor in order to have them properly positioned relative to the horizontal.

Heretofore it has been customary to drill holes in the concrete, insert expansion bolts into the holes and then screw into the expansion bolts. Unless the holes are drilled with extreme accuracy, they do not match the holes in the legs of the chairs, and after the holes are drilled it is impossible to adjust the positions of the chairs. Moreover, the concrete is weakened by drilling the holes and the expansion bolts tend to pull out.

The objects of the present invention are to overcome the difficulties incident to prior construction and to provide a construction whereby the chairs or other articles are firmly but adjustably held in position, whereby the floor or other surface is not materially weakened, whereby the attaching means is securely anchored in the floor, and whereby the articles may be readily adjusted and attached in proper alignment and properly spaced, either in a horizontal or inclined floor, and either in curved or straight lines.

According to this invention there is employed a series of anchors or bolts connected to a continuous slotted tapped or curved piece of steel or other material which is set in the cast, moulded or troweled surface of concrete, or other composition of combined materials, so as to serve as guides for the

levels of the finished floor or other surface and also as attachments for adjustably securing furniture or other objects. With my construction the objects may be attached by a single bolt or other fitting, the fitting being similar for all levels or pitch of floor and so arranged as to permit of play crosswise and from front to back to take up any inequalities in setting the inserts in the concrete or other material.

In order to disclose the nature of the construction I have illustrated it as applied to a theatre in the accompanying drawings, in which,—

Fig. 1 is a perspective view of a portion of a theatre floor and a portion of a theatre chair attached thereto according to this invention;

Fig. 2 is a vertical longitudinal section through the construction;

Fig. 3 is a vertical transverse section on line 3—3 of Fig. 2;

Figs. 4, 5 and 6 are perspective views similar to Fig. 1 showing modifications;

Fig. 4^a is an enlarged end view of channel and associated parts shown in Fig. 4; and

Figs. 7 and 8 are plan and elevation views, respectively, of a different application of the invention.

In the particular embodiment of the invention illustrated in Figs. 1, 2 and 3, 1 represents a floor of cast or molded material, such as concrete, the floor having steps 2 as in theatres, 3 and 4 represent legs of a chair and 5 represents a wood form upon which the floor is molded. An elongated tubular member 6 in the form of a channel is built into the floor, the channel member having overhanging portions in the form of turned flanges 7 separated by slot 8, the flanges being substantially flush with the top surface of the floor. The channel member not only serves as attachment means but also to guide the level in forming the floor surface. The channel member may be anchored in the floor by means of straps 9 extending over the channel member and thence downwardly to the floor. The straps 9 have feet 10 which serve temporarily to attach the anchor to the wood form 5 while the floor is being cast and which also serve to prevent the anchor from being pulled out after the construction is finished.

Associated with the chair legs is a yoke 11 having down-turned

bifurcated legs adapted to interfit with the feet of the chair legs and having a slot throughout its widened central portion. Fitting over this yoke is a U-shaped clip 13 provided with a centre opening.

5 A bolt 14 having a head 15 disposed in the channel 6 extends upwardly through the slots 8 and 12 and through the clip 13, nuts 16 being threaded on the upper end of the bolt. The head 15 of the bolt is elongated 10 as shown in Figs. 2 and 3 so as to underlie the overhanging flanges 7 of the channel 6 in normal position and so as to be removable in through the slot 8 when turned 90°.

15 In securing a chair in position, the yoke 11 is interengaged with the chair feet, the clip 13 is placed over the yoke 11, the head 20 of the bolt 14 is placed in the channel 6, the shank of the bolt is extended upwardly through the yoke 11 and clip 13, and the 25 nuts 16 are then threaded on the upper end of the bolt. Before the nuts are tightened, the chair is adjusted in the proper position, the bolt 14 sliding in the channel 6 for longitudinal adjustment and sliding in slot 12 for transverse adjustment. When the chair is in proper position the nuts are tightened.

30 If it is desired to have no projections extending above the surface of the floor, the strap 9 may be omitted or replaced with anchoring means which do not extend above the floor surface. If the chairs (or other articles) are to be arranged in curves, the 35 channel 6 will be curved at the desired degree of curvature.

The modification shown in Figs. 4 and 4^a 40 is similar to that shown in Figs. 1 to 3 but differs in the following particulars. The channel member 6' is narrower at the top than at the bottom and the flanges, instead of merely being turned in 90° as in the preceding figures are folded inwardly 45 through approximately 180° and then folded outwardly again through approximately 180°, so that each flange comprises two substantially vertical portions lying side by side. An important feature of this construction consists in that only narrow portions 50 of the beam are exposed at the floor surface, namely the portions joining the flanges with the sides through substantially 180° folds. Another feature of this modification is that the attaching bolt 14' engages 55 the flanges 7' edgewise, instead of flatwise as in Fig. 1, thereby affording greater strength and rigidity. Another feature shown in Figs. 4 and 4^a, which is not shown in Figs. 1 to 3, consists in bending 60 the strap 9' inwardly beneath the channel 6', to form shoulders 17 adapted to support the channel 6' on opposite sides while the concrete is being built up. It is to be understood that this feature may be employed 65 in the construction shown in Figs.

1 to 3. In Fig. 4 the yoke 11' is formed integrally with the chair legs instead of detachably connecting with the legs as in Figs. 1 to 3.

The modification shown in Fig. 5 differs 70 from the other modifications in that the yoke extending between the chair legs is formed of two straps 18 and 19, the straps being bent at 20, 21, etc. to hook over the flanges on the chair legs. In this construction the U-shaped clip 13' also functions to hold the two straps 18 and 19 together.

The modification shown in Fig. 6 differs from that shown in Fig. 5 in that the yoke 80 comprises two angle-iron pieces 22 and 23 having horizontal portions resting on the chair feet and vertical portions extending upwardly along the chair legs. In this construction, as in the construction of Fig. 5, the clip 13' holds the two parts of the 85 yoke together.

In the event that it is desired to secure articles in other than a straight line, as for example in fastening theatre seats in a curved row, the channel members are made 90 in sections and joined together as illustrated in Figs. 7 and 8, where 24 and 25 designate two adjacent sections of the channel. These sections are joined by means of a strap 26 which is riveted or bolted through the under side of the channel 24 as indicated at 27 and is detachably connected to the channel 25 by means of a lug 28 fast in the other end of the strap 26 and extending upwardly through an opening in the bottom of the 100 channel 25. As shown, the ends of the channel members are preferably beveled so that they may be set close together at an angle. Obviously this angle can be readily adjusted in attaching the channels.

105 I claim:

1. A building construction comprising a cast surface, a channel member provided with inturned flanges separated by a slot and cast in the surface with the inturned 110 flanges substantially flush with the surface, and an anchor member for said channel member having a portion bridging said slot and having means for supporting said first named member while said surface is being 115 cast.

2. A building construction comprising a cast surface, a channel member provided with inturned flanges separated by a slot and cast in the surface with the inturned 120 flanges substantially flush with the surface, and a member having a portion bridging the slot in said first named member for supporting the latter while said surface is being cast.

125 3. A building construction comprising a cast surface, a channel member provided with inturned flanges separated by a slot and cast in the surface with the inturned flanges substantially flush with the surface, 130

and a member folded over said channel member for supporting the latter while said surface is being cast.

7. A building construction comprising a cast surface, a channel member provided with inturned flanges separated by a slot and cast in the surface with the inturned flanges substantially flush with the surface, and a member folded over said channel member and having shoulders for supporting the latter while said surface is being cast.

5. A building construction comprising a cast surface, a channel member provided with inturned flanges separated by a slot and cast in the surface with the inturned flanges substantially flush with the surface, and a strap member bent about said channel member and having legs to support the latter while said surface is being cast, said legs being imbedded in said surface to anchor said channel member in place.

6. In a building construction, attachment means for adjustably fastening articles to the building comprising slotted members arranged on the article and building respectively with their slots extending transversely of each other, and a connecting device extending through said slots with portions 30 overhanging said members.

7. In a building construction, attachment means for adjustably fastening articles such as chairs or the like to a cast floor comprising a channel, provided with inturned flanges separated by a slot, cast in the floor with the flanges substantially flush with the floor surface, an anchor arranged on the article having a slot extending transversely of said channel, and a connecting device extending through said slots for adjustably connecting the channel and anchor together.

8. In a building construction, attachment

means for adjustably fastening chairs to a floor comprising fastening means anchored in the floor, and a yoke connecting with the 45 chair feet at its ends and attached to said fastening means intermediate its ends.

9. In a building construction, attachment means for adjustably fastening chairs to a floor comprising a yoke connecting with the 50 chair feet at its ends, and means for attaching the yoke to a floor intermediate its ends.

10. In a building construction, attachment means for adjustably fastening chairs to a floor comprising a series of channels set in 55 the floor end-to-end at angles to each other, means connecting the ends of said channels together to prevent endwise movement, and means for attaching chairs to said channels.

11. In a building construction, attachment 60 means for fastening chairs to a floor comprising a series of elongate anchors set in the floor end-to-end at angles to each other, and means for pivotally joining said anchors together so that said angles may be adjusted. 65

12. In a building construction, attachment means for adjustably fastening chairs to a floor comprising a yoke connected with the chair feet at its ends, and means including a slot in said yoke intermediate its ends for attaching the yoke to the floor. 70

13. In a building construction, attachment means for adjustably fastening chairs or the like to a cast floor comprising a channel, provided with inturned flanges separated by 75 a slot, cast in the floor with the flanges substantially flush with the floor surfaces, a yoke connecting the chair feet at its ends, and means for attaching the yoke intermediate its ends to said channel member. 80

Signed by me at Boston, Massachusetts, this eleventh day of April, 1921.

CLARENCE H. BLACKALL.
